CLEANING APPARATUS

Alick Clarkson, Bloomingdale Township,
Du Page County, Ill.

Application December 17, 1938, Serial No. 246,366

5 Claims. (Cl. 299—84)

This invention relates to a new and improved cleaning apparatus for producing and applying under pressure a cleaning fluid adapted to remove grease, oily deposits and other dirt from floors, walls, machinery, etc. The cleaning fluid may consist of steam, or a mixture of steam and a cleaning solution of hot water and a suitable detergent.

The apparatus comprising the steam generator, tanks for holding the water or cleaning solution, and fuel, the steam separator, and the manual and automatic control apparatus, are conveniently arranged in a compact unit that is preferably portable, although it may be mounted on a fixed foundation. The cleaning fluids are supplied through flexible hoses to sprayers or nozzles from which the output of cleaning fluids may be cut off or on as desired, although the generating apparatus may operate continuously when once started. The apparatus also comprises means for supplying rinse-water under pressure, or a rinsing solution, means for adding fuel-oil to the cleaning solution, means for supplying dry steam if desired, and many other features that will be apparent as the detailed description proceeds for selectively controlling the volume, pressure, and character of the cleaning fluids used. The generating system is quickly started, automatically controlled, and safe, and the entire unit is compact and the various parts are easily accessible for repairs or adjustment. The pumps and other movable parts of the apparatus are preferably driven from a single electric motor, although an internal combustion engine may be substituted if desired.

The principal object of the invention is to provide an improved cleaning apparatus of the type briefly described hereinabove and disclosed more in detail in the specification which follows.

Another object is to provide a steam cleaning apparatus comprising an improved generator adapted to supply a mixture of steam and hot water, together with a separator for removing the water and returning same to the tank when dry steam is desired.

Another object is to provide a single housing or chassis into which the tanks are built, and in which the generator and control elements are housed, provided with a removable bonnet or closures for permitting easy access to the generator and control mechanism.

Another object is to provide a cleaning apparatus including a plurality of water-pumps adapted to be used selectively, in any number, to provide the desired volume and pressure.

Another object is to provide an apparatus of

this character in which certain of the pumps can be used for furnishing either rinse-water, or other rinsing solution without passing these liquids through the steam generator.

Another object is to provide an apparatus of this character in which the generator and pumps operate continuously when once started, any excess liquids or fuel being returned automatically to the respective tanks.

Another object is to provide an apparatus for returning water to the tank instead of to the generator when a maximum steam pressure is reached.

Another object is to provide means for cutting off the fuel supply to the generator whenever the water supply to the generator falls below a predetermined pressure.

Another object is to provide means for adding fuel-oil to the water or solution supplied to the generator.

Numerous other objects and advantages of this invention will be apparent from the following detailed description of one approved form of apparatus constructed and operating according to the principles of this invention.

In the accompanying drawings:

Fig. 1 is a side elevation of the assembled apparatus, with one side of the bonnet opened to disclose the mechanism housed therein.

Fig. 2 is a perspective view showing the rear end of the apparatus with the housing closed.

Fig. 3 is a diagrammatic view, partially in vertical section, showing the parts disarranged from the actual positions as indicated in Fig. 1 so as to facilitate the disclosure of the piping circuits.

Fig. 4 is a central vertical section through the automatic steam pressure controlled water bypass.

Fig. 5 is a central vertical section through the automatic flow controller which regulates the supply of fuel to the generator in accordance with the water pressure.

Fig. 6 is a vertical section through one of the water-pumps; and

Fig. 7 is a vertical section through the lower portion of the water by-pass for the rinse pumps, the upper portion of this apparatus being similar to that shown in Fig. 4.

Referring first to Figs. 1 and 2, the greater portion of the mechanism is housed within a casting 1 which is preferably of box-like form having rounded end edges and a domed top portion so as to resemble somewhat the hooded portion of an automobile. This housing may be mounted on a fixed foundation but is preferably portable, in which case the lower portion of housing 1 serves

as the chassis. In the preferred form here shown, the housing is mounted centrally on a pair of similar wheels 2 having pneumatic tires 3, and the two end portions of the casing are supported by swiveled casters or small wheels 4 so that the apparatus can be easily turned into any desired position. The cushioned supporting connections 5 between casters 4 and the chassis are so designed that the casters can be elevated to leave the apparatus supported entirely by wheels 2 when the apparatus is being transported from place to place by the trailer attachment 6 which may be connected to an automobile or other vehicle. For movement through short distances, the casters 4 are lowered and the device is pulled or pushed into position by means of the hand-rail 7 at the rear end of the machine.

The main outlet 8 for the steam or cleaning mixture extends through the rear end of housing 1 and is provided with a main control lever 9. Outlet 8 has two branch outlets 10 and 11 from which extend similar hoses 12 leading to the hand-manipulated spraying devices indicated generally at 13. Each of these devices is provided with a spraying nozzle 14 and a hand-operated cut-off valve 15. Preferably this valve is of the type that automatically closes but may be opened by pressing in the hand-grip 16. Obviously there might be either one or a plurality of these applying nozzles 13, there being two shown by way of example in the present disclosure. Either one or both of the pair may be operated at any one time. At 17, 18, 19 and 20 are indicated a plurality of additional inlets or outlets to which hose connections may be attached. The purpose of these will become apparent as the description proceeds. For example one of these may be for attaching a hose to dispense rinse water. Another may be used for attaching a hose to fill one of the tanks.

Referring for the moment to Fig. 3 it will be noted that the lower portion of the housing or chassis is divided by a horizontal partition or platform 21, and a vertical partition 22 to form a large water tank 23 and a smaller fuel tank 24. The larger portion of the mechanism is supported above horizontal platform 21 in the upper chamber 25 of the housing, as indicated in Fig. 1. The side portions of the upper portion of the housing are in the form of a pair of removable or swinging closures 26 similar to the hood or bonnet of a automobile. Each side of the hood is provided with lifting handles 27 and retaining latches 28. By lifting one side of the hood easy access is obtained to the mechanism housed within chamber 25.

Referring again to Fig. 1, the steam generator indicated generally at 29 is centrally positioned within chamber 25. The generator comprises the burner head 30, and the spark plug 31 for starting the ignition. The combustion gases flow out through flue 32 to the stack 33 projecting upwardly at one end of housing 1. The moving parts of the apparatus are driven by a single electric motor 34, although an internal combustion engine might be substituted for this purpose. Motor 34 is energized through the extension cord 35 supported at the front of the casing which may be attached to any convenient electrical outlet. Motor 34 drives shaft 36 through the belt gearing 37, and the blower for supplying combustion air as well as the fuel pump (both hereinafter described) are mounted on shaft 36. The magneto 38 which supplies the ignition current to spark plug 31 is driven

from shaft 36 through belt 39. The crank 40 on rotary shaft 41 is driven from shaft 36 through suitable reduction gearing in the casing 42, and the pitman 43 secured at one end to crank 40 extends to and reciprocates the cross-head 44. The cross-head 44 is secured to a central portion of the double ended piston 45 which extends into the two similar water-pumps 48 and 49, (which will be hereafter referred to as the rinse pumps). An exactly similar pair of main water-pumps 46 and 47 are located directly back of the pumps 48 and 49 in Fig. 1 and not seen in that figure, but are shown diagrammatically in Fig. 3. The cross-head 44 also is attached to and drives the pistons of the second pair of pumps 46 and 47 so that all four of the pumps are simultaneously operated by pitman 43.

The remainder of the mechanism and piping can best be described by reference to the diagrammatic showing in Fig. 3, although such parts as are visible in Fig. 1 are indicated by the same reference characters as used in Fig. 3. The generator assembly indicated generally at 29 and the cooperating burner mechanism are preferably of the type disclosed more in detail and claimed in the copending applications of the same inventor, Serial No. 99,736, filed September 8, 1936 and Serial No. 149,466, filed June 21, 1937. The generator is of the coiled water-tube type comprising a plurality of substantially helical pipe loops 50, 51, 52 and 53 arranged co-axially about a central vertical axis so as to include a central heating space into which the combustion gases are projected. The outer coils serve as pre-heating coils whereas the inner coils are vaporizing coils. The pipe coils are successively connected at alternate ends of the bank of coils so that feed-water forced under pressure through inlet 54 into the outer pipe coil 50 will pass successively through the several coils and a mixture of water and steam will be discharged from the innermost coil 53 through the outlet connection 55. The greater portion of each turn of each coil is located in a horizontal plane, successive turns being connected by offsets 56. The axial lengths of the coils diminish from the inner coil 53 to the outer coil 50 giving the bank of coils a double frusto-conical configuration, and the bank of coils is mounted on and supported at the bottom by a refractory block 57 supported on platform 21, and is enclosed at the top by the annular shield 58. The successive turns or loops of adjacent coils are preferably staggered with relation to one another as shown, so that the hot gases from the central heating chamber will be forced to take a sinuous path between the several pipe turns thus securing a maximum surface contact with the coils and a maximum heat exchange. The gases, relieved of the greater portion of their heat, finally reach the outer annular space between the outer coil 50 and the enclosing casing 29' and then flow out through flue 32. The several turns of the coils are spaced apart and supported one from another by means of improved spacing means (not here shown but disclosed and claimed in said copending application Serial No. 99,736).

The liquid fuel, for example fuel-oil, is drawn from tank 24 through intake pipe 59, strainer 60, and pipe 61 to the rotary fuel pump 62 driven by shaft 36. This fuel pump may be of any suitable type and is not here shown in detail. The fuel is forced from the pump through pipe 63 to the burner head 30 and thence to the outlet nozzle 64. The head 30 contains a valve

which will only open under a predetermined minimum pressure so that no fluid will be discharged from nozzle 64 unless the fuel is forced through the valve under suitable pressure. The fire-pot 65 is supported centrally within air chamber 66 and is preferably centered symmetrically about the central vertical axis of the generator. The fire-pot is preferably metallic and comprises a substantially cylindrical side wall and is partially closed at the top by the wall or flange 67 which curves upwardly and inwardly and then downwardly to the upper central inlet 68 through which the atomized fuel is projected from nozzle 64. Combustion air is forced into the annular chamber 66 surrounding the fire-pot through inlet opening 69 leading from the blower casing 70 enclosing the blower 71 which is mounted on and driven by the shaft 36 and operated simultaneously with the fuel pump 62. An annular air-directing ring 72 positioned beneath the lower edge of fire-pot 65 but spaced therefrom directs air from chamber 66 upwardly into the fire-pot and also downwardly into the central heating space of the generator. Air is also directed downwardly through and beneath the stabilizing ring 73 interposed between nozzle 64 and the upper inlet to the fire-pot and surrounding a primary ignition zone. It will be noted that the air supply in chamber 66 completely surrounds the fire-pot 65 so that this air will be highly preheated before entering the combustion space. Circulating air currents are formed within the fire-pot 65 so that the combustion is very largely completed within this combustion chamber before being projected downwardly into the space surrounded by the water-tubes. This form of burner and its advantages are more definitely described and claimed in the copending application Serial No. 149,466 hereinabove referred to. In addition it may be here noted that the combustion flames, air-inlets and outlet flue are positioned at the top or uppermost portion of the generator and thus furthermost removed from the fuel supply and distributing devices so as to increase the safety of the assembled apparatus.

At 74 is indicated a water-supply pipe which may lead from one of the inlet connections 17 to 20 hereinabove described and which may be connected with the city water supply. Pipe 74 has one branch leading into the valve header or manifold 75, and another branch 76 leads down to a valve 77 in tank 23 that is automatically controlled by float 78. When the water level within tank 23 reaches a predetermined height, for example as shown in the drawings, valve 77 will be automatically closed, but the valve will open to admit more water when the water level falls. The water supply may be additionally controlled by a valve 79 positioned in the supply pipe 76. Tank 23 can be drained at any time by lifting the plug 80 by means of the pull-rod 80'. Any suitable soluble detergent or other cleaning material can be added to the water in tank 23 to form the desired cleaning solution.

The water or solution is drawn up from tank 23 through intake pipe 81 to the feed pipe 81' for the pair of pumps 46 and 47. Pump 47 is shown in vertical section in Fig. 6. The piston 45 extends through packing 82 and reciprocates in the pump cylinder 83. On the out-stroke of the piston liquid is drawn in from feed pipe 81' through inlet passage 84 and one-way or check valve 85 into cylinder 83. On the in-stroke of the piston the liquid in chamber 83 is forced out

through passage 86 and check valve 87 into the outlet chamber 88 from which leads pipe 89. The check-valves 85 and 87 may be of any suitable type so as to permit the flow of liquid only in an upward direction as shown in Fig. 6. A valve of the type here indicated is shown in section near the bottom of Fig. 4. As there shown, the movable valve member 91 is forced down by spring 92 to close passage 90, spring 92 being interposed between the movable valve member and an overhanging cage 93. Fluid pressure applied beneath the valve 91 will lift this member against the force of the spring, but when the pressure above the valve member 91 is greater it will be returned to close the passage 90. The four pumps 46, 47, 48 and 49 are all similar to the one described and shown in connection with Fig. 6. Outlet pipe 94 leads from pump 46, and it will be understood that water or solution is alternately forced upwardly by pumps 46 and 47 through the respective pipes 94 and 89.

Referring now to the water by-pass device shown in detail in Fig. 4, it will be noted that pipes 89 and 94 both lead into the chamber 95 near the lower end of the by-pass controller. The liquid is forced through passage 90 and the check-valve 91 already described into chamber 96 from which the liquid is forced out through pipe 97. Another passage 98 leads upwardly from chamber 95 into an upper chamber 99 from which a passage 100 leads downwardly to connect with a discharge pipe 101 adapted to carry liquid back into the tank 23 (see Fig. 3). The top of discharge passage 100 is normally closed by a one-way valve 102 (of the type already described) so that under normal conditions there will be no flow of liquid from chamber 99 through discharge pipe 101, all of the water or solution from pumps 46 and 47 flowing out through pipe 97. It may here be noted that an air-cushion vessel 103 (see Fig. 3) is connected with chamber 95 through pipe 104. As here shown pipe 104 is connected into pipe 94 adjacent the by-pass device. Vessel 103 is entirely closed except for the inlet and outlet passage through pipe 104. The alternate compression and expansion of the air within vessel 103 will tend to smooth out the pulsations of the liquid flows from pumps 46 and 47 and provide a more steady discharge of water through pipe 97.

Referring again to Fig. 4 a steam pressure chamber 105 is provided beneath a flexible diaphragm 106, the chamber 105 being connected through inlet passages 107 and 108 with a pipe 109 connected (as hereinafter described) with the steam chamber 110 of the separator 111 so that the pressure in chamber 105 will correspond closely with the pressure of the fluids discharged from the generator. A button 112 guided for vertical movement in frame 113 presses against the upper side of diaphragm 106. A plunger 114 connected at its lower end in button 112 projects upwardly through gland 115, spring-pressed packing 116, and guide tube 117 into and through the passage 100 so as to engage and open the valve 102 when plunger 114 is lifted. Button 112 and plunger 114 are normally held down by spring 118 engaging at its lower end a disk 119 resting on button 112 and engaging at its upper end against an adjustable collar 120 threaded on sleeve 117. The compression of spring 118 may be adjusted by rotating the collar 120 thus selecting the fluid pressure in chamber 105 that will be required to overcome the force of the spring and move plunger or stem 114 upwardly

to open the valve 102. Under normal operation valve 102 remains closed and all of the liquid from pumps 46 and 47 is forced through chamber 95 and out through pipe 97. However, if the pressure of the fluids discharged from the generator exceeds a predetermined maximum, the pressure in chamber 105 will become sufficient to lift the stem 114 and open valve 102 whereupon the liquid will flow through passage 98, chamber 99 and discharge pipe 101 back to tank 23.

Referring again to Fig. 3, it will be noted that the discharge from pump 47 through pipe 89 must pass through a two-way valve 121. Normally this valve will be turned so that the liquid will flow into chamber 95 along with the discharge from pump 46. However, valve 121 may be adjusted so that the output from pump 47 will flow through pipe 122 which is shunted around the by-pass device and connected into discharge pipe 101. When valve 121 is so adjusted, the output from pump 47 is forced directly back to tank 23 so that pump 47 is practically ineffective, and only the pump 46 supplies water or solution to the generator.

Pipe 97 from the by-pass device leads into a three-way fitting 123 from which pipe 124 leads into the lower portion of the fuel-flow control indicated generally at 125 and shown in detail in Fig. 5. The liquid flows from pipe 124 into the high-pressure chamber 126 which is separated by flexible diaphragm 127 from a low-pressure chamber 128. The movable valve-member 129 located in chamber 126 and carried by the lower end of stem 130 has a close lapped fit in outlet passage 131 from which supply pipe 132 leads into the inlet fitting 54 of the steam generator (see Fig. 3). The flexible diaphragm 127 is clamped between valve member 129 and a collar or nut 133 also mounted on stem 130 and located in low-pressure chamber 128. Connecting passages 134 in nut 133 and 135 in valve member 129 connect low-pressure chamber 128 with the outlet passage 131 and pipe 132.

When the pumps are not operating the pressure in chamber 126 will fall so that valve member 129 will be forced down into outlet passage 131 by a spring 136 (hereinafter described). When the pumps are operating a higher pressure will be developed in chamber 126 sufficient to flex diaphragm 127 upwardly and lift the valve 129 against the pressure of spring 136 and open a passage between chamber 126 and outlet 131. Valve 129 will only be lifted slightly out of the outlet passage 131 so that the higher pressure will not be communicated into upper chamber 128 and the valve will remain slightly elevated so as to permit a continuous flow of liquid into pipe 132 as long as the higher pressure is maintained in chamber 126. The stem or plunger 130 extends up through the spring-pressed packings 137 and 138 into and through the fuel-oil chamber 139. The rings or collars 140 positioned between packings 137 and 138 are provided with vent openings 141 communicating with vents 142 in the main casing 125 so that any liquid leakage from the chambers can escape through these vents.

Referring now temporarily to Fig. 3, a pipe 143 leads from fuel pump 62 into a four-way fitting 144 from which a pipe 145 leads into the upper end of the flow-controller (see Fig. 5). Pipe 145 discharges into the chamber 146 in a tubular member 147 formed at its lower end with an outlet valve-passage 148 in which the upper end of stem 130 has a closely lapped fit so as to normally close this passage. A dash-pot piston 149 is secured

on the upper portion of stem 130 and has a sliding fit in chamber 139. A circular plate 150 slideable on stem 130 is normally held up against the lower face of piston 149 by a weak spring 151.

5 When stem 130 is forced upwardly to close the valve 148, oil from the chamber above piston 149 will flow downwardly through passages 152 in the piston to fill the portion of the chamber below the piston, the plate 150 being pressed down against the resistance of weak spring 151 to permit a free downward passage of the oil. However, when stem 130 moves downwardly, under the influence of spring 136 which presses against the top of piston 149, the plate 150 will close up 15 against the bottom of the piston and only a restricted upward flow of oil can pass through the small openings 153 in plate 150. Consequently, the stem 130 can only move downwardly, to open valve 148, rather slowly. As a result any momentary loss of pressure in chamber 126, due to the pulsations of the reciprocating pumps, will be insufficient to open the fuel-valve 148, but when the pressure in chamber 126 is lowered for any material length of time due to the failure or stoppage of pumps 46 and 47 or the diversion of the liquid that would otherwise flow through pipe 124, the stem 130 will be lowered so as to open valve 148. The fuel will now flow freely through valve 148 into chamber 139 and then out through passage 154 and pipe 155. Referring to Fig. 3, the pipe 155 leads to the fitting 156 and thence through pipe 157 back into fuel tank 24. As a result, whenever the water flow fails so as to lower the pressure in chamber 126 of the flow controller, the valve 148 will be opened and the output from fuel pump 62 can flow through the low-resistance by-pass just described back to fuel tank 24. The pressure in pipe 63 leading from the fuel pump to the burner will then be reduced so that it will be insufficient to open the valve in burner head 30 and the supply of fuel to the burner will be cut off. Consequently the burner cannot operate unless water or solution is being forced into the generator coils.

45 Another fuel pipe 158 leads from the four-way fitting 144 to the maximum fuel-pressure valve 159, with an extension pipe 160 leading to the pressure gauge 161 located at the end of the main housing (see Fig. 2). Valve 159 can be adjusted by means of handle 162 for any desired maximum fuel pressure. When this fuel-pressure is exceeded, the excess fuel can flow from the valve through fitting 156 and pipe 157 back to fuel tank 24.

55 A third pipe 163 leading from four-way fitting 144 extends to a metering valve 164 and thence through pipe 165 into the feed-pipe 81' of pumps 46 and 47. By opening and adjusting the valve 164, a restricted flow of oil is permitted into the solution fed to pumps 46 and 47 and thence to and through the generator so that the cleaning spray solution may contain a desired proportion of oil.

The mixture of steam and hot water or solution is delivered from outlet 55 of the generator through pipe 166 into the upper portion of separator 111 (Fig. 3). The liquid in this fluid stream flows down past the shields or diverters 167 and 168 into the lower portion of the separator from which it flows out through pipe 169 back into the supply tank 23, assuming that the valve 70 in pipe 169 is open. Under these conditions the steam will flow around shield 167 and thence upwardly into the steam chamber 110 and out through pipe 171 and fitting 8 to

the spray nozzles. If valve 170 is closed the separator will become substantially inoperative and the entire fluid stream of mixed steam and solution will flow through the separator and to the nozzles. A blow-off valve or safety valve 172 is connected into steam chamber 110. A pipe 173 also leads from steam chamber 110 to the fitting 174 with which is connected the steam-pressure indicator 175 located at the end of the machine as shown in Fig. 2. The steam-pressure pipe 109, already described, also leads from fitting 174 into the inlet 108 of the by-pass device already described.

In operation, if the pressure of the fluid discharged from the generator exceeds a predetermined maximum, the pressure thus communicated through pipes 173 and 109 will cause the output from the pump 46 and/or 47 to be diverted back to tank 23, and as a consequence the pressure transmitted through flow-controller 125 will be lowered so that the fuel output from fuel pump 62 will also be diverted back to the fuel tank 24 and the burner will cease to operate. When the output pressure from the generator falls below the permitted maximum the by-pass device will again direct the water to the generator, and the flow-controller will automatically cut off the fuel by-pass so that fuel will again be forced through the burner and the fires will be automatically ignited by spark plug 31.

The rinse pumps 48 and 49 operate in exactly the same manner and simultaneously with the main water pumps 46 and 47. The feed pipe 176 for the rinse pumps is connected through pipe 177 with the supply manifold 75 already described. If plain water is to be used for rinse purposes, the valve 178 is opened so that water can flow in from supply pipe 74 through manifold 75 and thence through pipes 177 and 176 to the rinse pumps. If some other agent, for example an acid solution, is to be used valve 178 is closed and valve 179 is opened so as to permit this liquid to be drawn in through pipe 180 which may be supplied through one of the fittings 17 to 20 at the end of the machine. As a third alternative the rinse pumps 48 and 49 may be used to supplement the main pumps 46 and 47 in supplying solution from tank 23 to the generator. In this case valves 178 and 179 are closed and valve 181 opened so that solution from the tank may be drawn up into manifold 75 through intake pipe 182. The output from pump 48 flows over through pipe 183 to join with the output from pump 49, the combined liquid steam flowing through pipe 184 into bypass device 185. An air-vessel 186 (similar to vessel 103 and functioning for the same purpose) is connected into by-pass device 185 through pipe 186'. The by-pass 185 is for the most part substantially identical in structure with the one previously described and shown in Fig. 4. However, this by-pass 185 operates in response to variations in the liquid pressure instead of variations in the steam pressure beyond the generator. The lower portion of device 185 is shown in Fig. 7, it being understood that the upper portion of this structure is the same as that shown in Fig. 4. The output from the rinse pumps flows from pipe 184 into chamber 95 and thence as before through passage 90 and valve 91 into chamber 96 and is discharged through pipe 187. However, in this by-pass there is no steam connection to chamber 105 beneath diaphragm 106, but chamber 105 is connected

through passage 188 with the water chamber 96. As a consequence, if the pressure in this water system becomes excessive, diaphragm 106 will be lifted to open the valve in the top of the by-pass and permit the liquid to flow out through pipe 189. It will be noted that by-pass 189 does not discharge back into tank 23 like pipe 101, but instead pipe 189 is connected into the feed pipe 176 for the rinse pumps. Consequently, when there is no suitable outlet for the liquid from pumps 48 and 49 and the pressure in the by-pass device becomes excessive, the liquid will simply be shunted around through pipe 189 to the feed pipe 176, again flowing through the pumps. The reason for this change is that rinse pumps 48 and 49 are sometimes used for handling water or a different solution from that contained in tank 23 and it is undesirable to discharge this other liquid into the tank.

Normally the output from rinse pumps 48 and 49 will flow through pipe 187 into the discharge manifold 190. When water or some other rinsing liquid is fed to the rinse pumps from inlet pipes 74 or 180, the valve 191 in manifold 190 will be opened so that this liquid will be discharged through pipe 192 and an outlet at the end of the casing 1 to which a hose connection leading to a sprayer or nozzle is attached. When the rinse pumps 48 and 49 are used to supplement pumps 46 and 47 in supplying solution to the generator, valve 191 is closed and valve 193 opened. The liquid from manifold 190 will now flow through pipe 194 back into fitting 123 and thence along with the output from pumps 46 and 47 through pipe 124 into the fuel-flow controller 125. Alternatively, it may sometimes be desirable to feed the solution drawn from tank 23 through pumps 48 and 49 into the hot-fluid stream discharged to fitting 8, without passing this liquid through the generator. To do this valves 191 and 193 are closed and valve 195 is opened so that the liquid from the rinse pumps flows through pipe 196 into the discharge pipe 171 leading from the steam separator.

It will now be apparent that any number of the pumps 46, 47, 48 and 49 can be utilized for furnishing liquid to the generator, although these pumps are all constantly operating. If only one pump is to be used for this purpose, the stream from pump 47 will be directed back to tank 23 by suitably adjusting valve 121, and valve 193 will be closed so that the line from pumps 48 and 49 to the generator is cut off. If two pumps are to be used, the output from pump 47 is added by suitably turning valve 121. If three pumps are to be used, the output from pump 47 is shunted through valve 121 back to tank 23 but valves 181 and 193 are opened so that rinse pumps 48 and 49 will add their output to that of pump 46. Finally, the output from all four of the pumps can be forced to the generator in an obvious manner. Also the pumps 48 and 49 can be used at any time for furnishing either rinse water or a rinse liquid or solution of other type without passing these liquids through the generator.

The operation of the generator is entirely automatic as long as driving motor 34 is in operation. The burner cannot operate unless an adequate supply of water or solution is being forced through the generator coil, and as long as an excess pressure is developed at the generator outlet the supply of water to the generator coils and

fuel to the burner will be stopped. The flow of both liquids starts again automatically as soon as this output pressure is reduced. Any excess liquids from the several pumps are returned automatically to the supply tanks, or shunted back through the rinse pumps.

In order to start the generator, it is merely necessary to throw a switch starting the motor 34 and in a very short time a supply of cleansing fluid under the necessary pressure will be available at the spray nozzles. The discharge of this cleansing fluid under pressure is controlled entirely by the hand valves 15 at the nozzles, and during the stand-by periods when the nozzles are not being used the generator and pumps continue to operate, any excess pressures developing being automatically taken care of by the mechanism hereinabove described.

I claim:

1. In a cleaning apparatus of the character described, a tank for holding liquid cleanser, a tank for fuel oil, a steam generator comprising a burner, means comprising a fuel pump for delivering oil from the fuel-tank to the burner, means comprising a pump, a feed-pipe leading from the liquid tank to the pump, and a supply pipe leading from the pump to the generator for forcing liquid into the generator, a discharge conduit for delivering cleaning fluids from the generator, means for driving the pumps, a pipe-connection leading from the pressure side of the fuel-pump into the feed-pipe to the liquid pump, and a metering valve in the pipe-connection for feeding a restricted amount of oil into the liquid delivered to the generator.

2. In an apparatus of the character described, in combination with a generator and separate means for respectively forcing fuel and water to the generator, a by-pass conduit for diverting the fuel from the generator, a valve in said conduit, a pressure chamber through which the water is passed before reaching the generator, a flexible diaphragm forming one wall of this chamber, a plunger for closing the valve, a spring urging the plunger in one direction to open the valve, the plunger being associated with the diaphragm so that it will be moved in the opposite direction against the force of the spring to close the valve when operating water pressure is in the chamber, and a dash-pot associated with the plunger for retarding its movement in a valve-opening direction so that momentary variations in the water pressure within the pressure chamber will be ineffective to open the valve.

3. In an apparatus of the character described, in combination with a generator and separate means for respectively forcing fuel-oil and water to the generator, a by-pass conduit for diverting oil from the generator, said conduit comprising an oil chamber and a valve opening for admitting oil to the chamber, a plunger movable through the chamber for closing the valve-opening, a spring urging the plunger in a valve-opening direction, water-pressure operated means for moving the plunger against the force of the spring to close the valve, a dash-pot piston mounted on the plunger and movable in the oil-chamber, and means associated with the piston for retarding its movement in a valve-opening direction so that momentary variations in the water pressure within the pressure chamber will be ineffective to open the valve.

4. In a cleaning apparatus of the character described, a tank for holding liquid cleaner, a steam generator comprising liquid circulating tubing, means comprising a pump and a supply pipe for delivering liquid from the tank to the generator, a steam-separator, a conduit for delivering mixed hot liquid and steam from the generator to the separator, an outlet for steam or mixture of steam and liquid cleaner leading from the separator, a drain connection leading from the separator to the liquid tank, and a valve in the drain connection and adapted to be selectively positioned to open the drain to permit the liquid separated from the steam to discharge from the separator into said liquid tank or to close said drain, whereby the mixture of steam and liquid is discharged from the separator through said outlet.

5. In an apparatus of the character described, in combination with a generator and separate means for respectively forcing fluid and water to the generator, a by-pass conduit for diverting fuel from the generator, a valve in said conduit, a pressure chamber through which the water is passed before reaching the generator, a flexible diaphragm forming one wall of this chamber, a plunger for closing the valve, a spring urging the plunger in one direction to open the valve, the plunger being associated with the diaphragm so that it will be moved in the opposite direction against the force of the spring to close the valve when operating water pressure is in the chamber, and means for yieldably retarding the movement of the plunger in a valve-opening direction.

ALICK CLARKSON.

CERTIFICATE OF CORRECTION.

Patent No. 2,350,876.

June 6, 1944.

ALICK CLARKSON.

It is hereby certified that error appears in the printed specification of the above numbered patent requiring correction as follows: Page 5, first column, line 56, for the word "steam" read --stream--; and that the said Letters Patent should be read with this correction therein that the same may conform to the record of the case in the Patent Office.

Signed and sealed this 1st day of August, A. D. 1944.

Leslie Frazer

(Seal)

Acting Commissioner of Patents.
